UNITED STATES PATENT OFFICE.

GUIDO HORN, OF BERLIN-WEISSENSEE, GERMANY.

MECHANISM FOR REGULATING THE TENSION IN MACHINES FOR WINDING AND CONVEYING STRIPS OF FABRIC AND SIMILAR GOODS.

Application filed July 26, 1926, Serial No. 125,080, and in Germany October 18, 1923.

My invention relates to improvements in mechanism for regulating the tension in machines for winding and conveying strips of fabric and similar goods.

5 A considerable draw-back of known machines of this kind is the fact that in most cases they pull the material too quickly, whereby the quality of the material is impaired, or the material is wound and conveyed under variable and unequal tension.

10 To avoid the first mentioned inconvenience it has hitherto only been possible to use slow coupling driving devices whereas special speed regulators sometimes in combination with special driving means have been employed to overcome the variable tension.

15 The object of the present invention is to provide means for always conveying or winding the material with the same tension

20 under all circumstances even if the winding or conveying machine is suddenly started. For this purpose either the material to be conveyed or wound, or the flexible driving means of the machine is passed over a

25 swingably arranged feeler device which causes the desired tension of the material or determines the power necessary for carrying out the working process. This feeler device in the following simply called "tension lever" has a direct balancing effect upon the winding or conveying machine for maintaining a uniform tension or a uniform consumption of power. If on account of any obstacle the resistance of the material to be conveyed rises, the tension lever effects correspondingly great uncoupling of the drive so that only such an amount of material can be conveyed as is admissible without raising the tension of said material. Therefore

30 even a quick coupling of such a machine does not cause a greater tension of the material than that corresponding to the adjustment of the tension lever. The conveying of the material is effected with such a speed

35 only as to cause the tension applied to the material to overcome the amount of the machine and the brake resistance of the holding means delivering the material, or as is permitted by the delivery speed of the holding means without raising the tension of the material. If the resistance is greater than the adjusted tension, the material to be wound or conveyed is not moved at all so that a tearing of the material is absolutely

40 prevented.

The machines according to the invention may be provided with any suitable sliding- or friction-coupling. In the examples shown brake band couplings are employed. These couplings may be so constructed that 40 the conveying machine or the winding drum is started when the brake is pulled and automatically disconnected when the brake is loosened, or else the couplings may be so constructed that they constantly tend to act 45 as long as they are not prevented therefrom by the braking action of the brake band. Depending upon the kind of coupling used a negative and positive action respectively of the devices comes into consideration. 50

The mode of operation of the machine will now be described with reference to the accompanying drawing wherein,

55 Figure 1 is a diagrammatic view of one form of my invention.

Figure 2 is a diagrammatic view of another form of my invention.

Figure 3 is a detail plan view of a portion of the same.

60 The material 1 is fed from the spool 10 over the idler 9 and the direction of travel is such as to effectually act upon the herein-after described mechanism according to the tension of the web of material 1. The spool 10 is mounted on a shaft 11 and has a link 80 connection 14 with a drive shaft 13. The drive shaft 13 includes the clutch 5 and a drive pulley 12. A lever 2 is pivotally connected to a stationary support and has one end arranged to engage the web 1 to be actuated by the latter according to the tension thereof. This lever 2 carries a cam 4 coacting with a pivoted arm 7 that is connected by the link mechanism of connector 16 with the band 6 of the clutch. A coil spring 3 urges the lever 2 into a normal position so that the lever will be sure to follow the web 1. A second spring 8 is arranged to act upon the arm 7, to draw the same in a direction to operate the band 6 through the connection 16 and thus it may be seen that as the lever 2 swings about its pivot, the spring 8 will act to increase or decrease the engagement of the band 6 with the clutch and thereby controlling the amount of power 90 transmitted to the shaft 11 and spool 10. 100

In Figures 2 and 3 I have illustrated the web 1^B as passing from the spool 10^B over the idler 9^B with a portion of its length so arranged as to operatively engage one end 110

of the lever 2^B. This lever 2^B is pivoted to a stationary support and is urged toward the material by the coil spring 3^B. In this particular case the arm 7^B has one end pivoted 5 to a stationary support and the other end connected to a spring 8^B, the brake band 6^B has one end secured to a stationary support and its other end connected to the arm 7^B to draw the band into tight engagement 10 with the clutch 5^B when the spring 8^B is allowed to contract in a manner now to be described. Cam 4^B in this particular instance has a relative arrangement to operate and depress arm 7^B when the web of material 15 becomes slack. Thus it will be seen that in this particular case the braking action on the clutch is in proportion to the tension of the web 1^B. That is to say as the lever swings downwardly it will depress the arm 20 7^B so as to release the engaging action between the band and the clutch.

From the foregoing description taken in connection with the accompanying drawing it will be apparent that as the tension of the material 1 increases or decreases, the lever 2 25 will be swung about its axle for manipulating the various parts for increasing or decreasing the amount of power transmitted to the feed mechanism and thus the uniform 30 tension of the material is assured.

The device according to the invention is not to be limited to the conveyance of fabric strips but may also be used for conveying and winding cables, wifes, threads and the

like. Moreover the new device may also be used as a safety device for preventing over-loading in the most different systems of power transmission by belts, cables, chains and similar driving means.

What I claim is:

1. In combination, a drive shaft, web feeding mechanism, a drive connection between the shaft and said mechanism including a friction clutch, a brake band controlling the operation of the clutch, a pivotally mounted 45 arm operatively connected to said band, a spring normally acting to force the arm in one direction, a cam for moving the arm in an opposite direction, and a lever connected to said cam and engaging the web to be operated thereby according to the tension of the web.

2. In combination, web feeding mechanism, driving means therefor including a friction clutch, a brake band having one end secured to a stationary support and passed around said clutch, a pivoted arm connected to the other end of the band, a spring acting on the arm to draw the band into engagement with said clutch, a cam acting upon the 60 arm to move the same to release the band from the clutch, a lever connected to said cam, and having a free end operatively engaging the web in the travel of the latter.

In witness whereof I have hereunto set my hand.

GUIDO HORN.
